US00D999228S

(12) **United States Design Patent** (10) **Patent No.:** **US D999,228 S**
(45) **Date of Patent:** **** Sep. 19, 2023**

(54) **DISPLAY SCREEN OR PORTION THEREOF
WITH A GRAPHICAL USER INTERFACE**

(71) Applicant: **AHAM CO., LTD.**, Seoul (KR)

(72) Inventors: **Min Seo Kim**, Seoul (KR); **Yong Su Lee**, Seoul (KR)

(73) Assignee: **AHAM CO., LTD.**, Seoul (KR)

(**) Term: **15 Years**

(21) Appl. No.: **29/819,406**

(22) Filed: **Dec. 15, 2021**

(30) **Foreign Application Priority Data**

Jun. 16, 2021 (KR) 30-2021-0028621

(57) **CLAIM**

The ornamental design for a display screen or portion thereof with a graphical user interface, as shown and described.

DESCRIPTION

The FIGURE is a front view of a display screen or portion thereof with a graphical user interface, showing our new design.

The outermost broken lines illustrate a display screen or portion thereof and form no part of the claimed design. The remaining broken lines, illustrating portions of the graphical user interface, form no part of the claimed design.

1 Claim, 1 Drawing Sheet
